CONTROL SYSTEM

Maurice E. Reagan, Pittsburgh, Pa., assignor to
 Westinghouse Electric & Manufacturing Company, East Pittsburgh, Pa., a corporation of Pennsylvania

Application March 19, 1942, Serial No. 435,361

12 Claims. (Cl. 177—311)

The present invention relates, generally, to control systems, and, more particularly, to remote control systems for automatic reclosing circuit breakers.

Automatic reclosing circuit breaker control systems commonly have closing and tripping apparatus associated with the controlled circuit breaker in a switching yard or breaker station and other control and indicating apparatus in a nearby substation or control room, the two sets of apparatus being connected by control conductors extending between the apparatus at the breaker and the apparatus in the control room through a conduit. Heretofore such systems have required a considerable number of control conductors between the control station and the breaker yard or station, thus necessitating the use of a control conduit having a large control circuit capacity. This resulted in high purchase and installation costs of the control conductors which extend between the control station and the controlled station.

An object of the present invention is to provide an automatic reclosing circuit breaker control system which shall require a minimum of control conductors extending between a control point and the point at which the controlled breaker is disposed, and which shall be simple and efficient in operation and inexpensive to manufacture, install, operate and maintain.

These and other objects and advantages of the invention will be apparent from the following detailed description taken in connection with the accompanying drawing in which Figs. 1 and 2 are diagrammatic representations of circuit breaker control systems which embody the principal features of my invention in which like reference characters designate like elements of apparatus.

In practicing the invention, in the embodiment of Fig. 1, a circuit breaker 4 having a closing coil 6, a tripping mechanism 8 and auxiliary relays 10 and 12 associated therewith, is disposed in a breaker yard, bank or station, and is connected with a control room or station by means of the conductors 14, 16 and 18. At the control station a protective relay 20, a manually operable control device 22, an auxiliary relay 24, an alarm 26, and indicating lamps 28 and 30 are connected to control and be controlled by the circuit breaker 4 over the control conductors 14, 16 and 18. The embodiment of the invention of Fig. 2 is generally the same except that it also includes a toggle relay 32, a reactor 34, and a timing device 36.

Considering the invention in detail, in the em-

bodiment of the invention of Fig. 1, the manually operable control device 22 comprises operating members 40 and 42 which are disposed to operate circuit control devices 44 and 46, respectively, and to actuate a pivot arm 48 by means of members 50 and 51 to, in turn, actuate a contact element 52. The pivoted arm 48 is disposed to be held in actuated position by a spring member 53. When the operating member 40 is actuated, the contact element 52 is moved to closed circuit position to close an energizing circuit for the relay 10 extending from positive potential indicated by the plus sign, through conductors 54, 55 and 56, the contact element 52, a conductor 58, a contact element 60 of the relay 24, the conductor 18, the winding of the relay 10, a conductor 62, a contact element 64 actuated by the circuit breaker 6, a conductor 66, a contact element 68 of the relay 12, and conductors 70 and 72 to the other terminal of the source of control power. The source of control power indicated by the plus and minus signs is understood to be a source of direct current potential such as a battery which is common to the control station and the breaker station.

The actuation of the relay 10 will close an energizing circuit for the closing coil 6 of the circuit breaker 4 extending from positive control potential through a conductor 74, a contact element 76 of the relay 10, a conductor 78, the winding of the closing coil 6, conductors 80 and 82, a contact element 84 of the relay 10, and conductors 86 and 12 to negative control potential. When the circuit breaker moves towards closed position, its contact element 64 will be moved to open circuit position and a current limiting resistor 88, which is connected between the conductors 62 and 66 in shunting relation with the contact element 64, will maintain an energizing circuit for the relay 10, and the relay 10 will be maintained in the operated position. The resistor 88 may be of such value of resistance as to permit sufficient current to flow in the winding of the relay 10 to hold the relay 10 in operative position but to prevent sufficient current to flow in the winding 45 of the relay 10 to operate the relay in the released position.

The operation of the circuit breaker 6 with relay 10 held closed will close an energizing circuit for the relay 12 extending from positive control potential through the conductor 74, the contact element 76, a conductor 90, the winding of the relay 12, a conductor 92, a contact element 94, the conductor 82, the contact element 84, and the conductors 86 and 72 to negative control potential. The closure of the circuit breaker 6 will

also close an energizing circuit for the auxiliary relay 24 at the control station extending from positive control potential, through conductors 54 and 96, the winding of the relay 24, the conductor 16, a contact element 98 actuated by the circuit breaker 4, the conductors 80 and 82, the contact element 84 and the conductors 86 and 72 to negative control potential. The relay 12 will open the holding circuit for the relay 10 by moving its contact element 68 to open circuit position and the relay 24 will open the energizing circuit for the relay 10 by moving its contact element 60 from the lower contact position to the upper contact position. The deenergization of the relay 10 will cause its contact element 76 to open the circuit for the relay 12 and the winding of the closing coil 6 of the circuit breaker 4. The movement of the contact element 60 of the relay 24 to the upper contact position will close an energizing circuit for the alarm 26 extending from positive control potential through the conductors 54 and 100, the contact element 60, a conductor 102, the alarm 26, and conductors 104 and 105 to negative control potential at the control station. When the circuit breaker 4 is moved to closed position the latch device 8 will move its detent 106 behind the detent 108 actuated by the circuit breaker 4 to hold the circuit breaker in closed circuit position until the detent 106 is removed from the path of the detent 108 by the energization of the tripping device 8.

In the closed position, the circuit breaker 4 will close an energizing circuit for the indicating device 28 extending from positive control potential at the control station through conductors 54 and 110, the indicating device 28, conductors 112, 114, 14 and 116, the winding of the tripping mechanism 8, a conductor 118, a contact element 120 actuated by the circuit breaker, and conductors 122 and 72 to negative control potential at the breaker station. When the circuit breaker 4 is in the open circuit position, the contact element 120 will close an energizing circuit for the indicating device 30 at the control station extending from positive control potential at the breaker station through conductors 14 and 124, the contact element 120, conductors 14, 114 and 112, the indicating device 30 and conductors 126 and 105 to negative control potential at the control station.

The relay 24 will be held in actuated position by the engagement of its detent 128 by a detent 130 which may be removed to release the relay 124 by actuating a manually operable member 132 against the bias of a spring member 134.

The circuit breaker 4 may be tripped by a protective relay 20 whose contact element 136 is disposed to close an energizing circuit for the tripping mechanism 8, extending from positive control potential at the control station through the conductors 54 and 55, the contact element 136, the conductors 114, 14 and 116, the winding of the tripping mechanism 8, the conductor 118, the contact element 120, and the conductors 122 and 72 to negative control potential at the breaker station. The circuit breaker may also be tripped by actuation of the contact element 46 which will close a shunting circuit for the contact element 136 extending from the conductor 54 through conductors 138 and 140, the contact element 46, and the conductor 14 to conductor 114.

The circuit breaker 4 may be closed by the contact element 44 when the relay 20 is actu-

ated in a circuit which extends from positive control potential at the control station through the conductors 54 and 138, the contact element 44, conductors 142 and 13, the winding of the relay 10, the conductor 62, the contact element 64, the conductor 66, the contact element 68, and the conductors 70 and 72 to negative control potential at the breaker station.

It is to be understood that the tripping device 8 may be so designed as to be actuated only when the full potential from the control source is applied thereto and that it will not be actuated when the winding of the trip device 8 is connected in circuit with the indicating device 28.

In the operation of the system of Fig. 1, the circuit breaker 4 may be tripped by the protective device 20, and the contact element 64, together with the contact elements 60 and 52 in normal closed position, will cause the relay 10 to be energized. The relay 10 will close the circuit breaker 4 which, in turn, will energize the relay 24. The relay 24 will open the energizing circuit for the relay 10 and will be latched in operated position. When the circuit breaker 4 is thus closed, if the contact element 136 is still in the closed position or if the protective relay operates again thereafter, the circuit breaker will again be tripped, but this time it will not be reclosed for the reason that the contact element 60 which is in the energizing circuit of the relay 10 will be held in open circuit position with respect to that circuit by the latch members 128 and 130.

On the first tripping of the circuit breaker 4, the indicating device 28 will be deenergized and the indicating device 30 will be energized, and when the circuit breaker is reclosed, the indicating device 30 will be energized, the indicating device 28 will be deenergized, and the alarm 26 will be energized.

If the circuit breaker 4 stays closed upon reclosure, which will be indicated by the indicating device 30, the operator may actuate the detent 130 to release the relay 24, thus deenergizing the alarm 26 and permitting the contact element 60 to prepare the energizing circuit for the relay 10 to be operated by the circuit breaker 4 when it is next tripped.

When it is desired to trip the circuit breaker 4 manually without reclosing it automatically, the contact element 46 may be actuated, and when this is done the contact element 52 will be moved to open circuit position, thereby opening the energizing circuit for the relay 10 and preventing the relay 10 from being energized when the circuit breaker 4 opens.

In the embodiment of the invention of Fig. 2, the energizing circuit for the relay 10 extends from positive control potential at the control station, through conductors 54, 55 and 56, the contact element 52, conductors 144 and 146, a contact element 148 of the toggle relay 32, the conductor 18, the winding of the relay 10, the conductor 62, the contact element 64, the conductor 66, the contact element 68, and conductors 70 and 72 to negative control potential at the breaker station. When the circuit breaker 4 is closed by the mechanism at the breaker station, as described hereinabove in connection with the embodiment of the invention of Fig. 1, a solenoid 154 of the toggle switch 32 will be energized in a circuit extending from positive control potential at the control station through conductors 54, 150 and 152, the winding of the solenoid 154, the conductor 16, the contact element

98, the conductors 80 and 82, the contact element 84, and the conductors 86 and 72 to negative control potential at the breaker station.

The reclosure of the circuit breaker 4 will cause an energizing circuit for the indicating device 28 to be closed extending from positive control potential at the control station through conductors 54 and 156, the indicating device 28, a conductor 158, the saturating winding 160 of the reactor 34, a conductor 162, the conductors 114 and the winding of the tripping device 8, the conductor 118, the contact element 120 and the conductors 122 and 72 to negative control potential.

When the solenoid 154 is energized, the contact elements 148 and 164 will be actuated to left-hand position to open the energizing circuit for the relay 10 and close an alternating current circuit for the timing device 36 extending from one terminal of a source of alternating current through conductors 165 and 166, the winding of the timing device 36, a conductor 168, the contact element 164, a conductor 170, a reactive winding 172 of the reactor 34, a conductor 174, another reactive winding 176 of the reactor 34, and conductors 178 and 180 to the other terminal of the alternating current source. The reactor 34 is so designed that, when the current which actuates the indicating device 28 is flowing in the winding 160 of the reactor 34, the core of the reactor 34 will be sufficiently saturated to reduce the reactance of the reactive windings 172 and 176 and to thus permit sufficient current to flow to actuate the timing device 36. The timing device 36 may comprise an inductive disk timer or any equivalent device actuatable by alternating current to close its contact element 181 at a predetermined time after its initial energization.

With the contact element 148 in left-hand circuit closing position, after the predetermined time interval of the timing device 36, the contact element 181 will be moved to closed circuit position to close an energizing circuit for the toggle relay 32 extending from positive control potential at the control station through conductors 54, 150 and 182, the contact element 148, a conductor 184, a solenoid winding 186 of the toggle switch 32, the contact element 181, the conductors 114 and 162, the indicating device 30 and conductors 187 and 105 to negative control potential. The actuation of the toggle switch 32 by the solenoid 186 will open the energizing circuit for the timing device 36 by the movement of the contact element 164 to open circuit position and will prepare the energizing circuit for the relay 10 by moving the contact element 148 to the right-hand circuit closing position.

In the operation of the embodiment of the invention of Fig. 2, when the circuit breaker 4 is tripped by the protective device 20 it will be immediately reclosed, and, if it remains closed for the time period of the timing device 36, the system will be reset to again immediately reclose the breaker when it is tripped. However, if the circuit breaker does not remain closed when reclosed, but trips again within the time interval determined by the timing device 36, the contact element 120 will move from the upper contact position to deenergize the saturating coil 160 which will so increase the reactance of the windings 172 and 176 as to prevent further actuation of the timing device 36, and the contact element 181 of the timing device 36 will therefore be prevented from moving to closed circuit position to

again prepare the energizing circuit for the reclosing relay 10. The indicating device 28 will be energized as explained hereinbefore, and the indicating device 30 will be energized when the circuit breaker 4 is in open position in a circuit extending from positive potential from the breaker station, through the conductors 74 and 124, the contact element 120, the conductors 14, 114 and 162, the indicating device 130 and the conductors 187 and 105 to negative potential at the control station.

It is to be particularly noted that the systems of both embodiments of the invention operate over only the three control conductors 14, 16 and 18 between the control and the breaker stations to provide automatic trip, reclosure and indication for the circuit breaker 4, as well as manual control of the circuit breaker 4 by the contact elements 44 and 46, thus requiring a minimum number of control conductors extending between the control and breaker stations.

In compliance with the requirements of the patent statutes, I have shown and described herein the preferred embodiment of my invention. It is to be understood, however, that the invention is not limited to the precise constructions shown and described, but is capable of modification by one skilled in the art, the embodiments shown herein being merely illustrative of the principles of my invention.

I claim as my invention:

1. In an automatic reclosing circuit breaker control system, first, second, and third control conductors extending between a circuit breaker and a control station, means actuatable at the control station including said first conductor for closing the breaker, means actuatable at the control station and including said second conductor for tripping the circuit breaker, means responsive to the opening of the circuit breaker and including said first conductor for automatically reclosing the breaker, and means at the control station operable in response to the reclosure of the breaker by means including said third conductor to render the said means responsive to the opening of the breaker ineffective to effect a second reclosure of the breaker in the event that the breaker is tripped following the first reclosure thereof.

2. In an automatic reclosing circuit breaker control system, first, second, and third control conductors extending between a control station and a circuit breaker, closing means for the circuit breaker, tripping means for the circuit breaker, means actuatable at the control station and including said first conductor for actuating the closing means, means actuatable at the control station and including said second control conductor for actuating said breaker tripping means, means responsive to the opening of the circuit breaker and including said first control conductor for actuating said breaker closing means to automatically reclose the breaker, and means at the control station operable in response to the reclosure of the breaker by means including said third control conductor for rendering the means responsive to the opening of the breaker ineffective to effect a second reclosure of the breaker in the event that the breaker is tripped following the said first reclosure thereof.

3. In an automatic reclosing circuit breaker control system, first, second, and third control conductors extending between a control station and a circuit breaker, closing means for the circuit breaker, tripping means for the circuit breaker, means actuatable at the control station and in-

cluding said first control conductor for operating the closing means, means actuatable from the control station and including said second control conductor for actuating said breaker tripping means to open the breaker, means responsive to the opening of the circuit breaker and including said first control conductor for actuating said breaker closing means to automatically reclose the breaker, and means at the control station operable in response to the reclosure of the breaker by means including said third control conductor to render the means responsive to the opening of the breaker ineffective to effect a second reclosure of the breaker in the event that the breaker is tripped within a predetermined time interval following the first reclosure.

4. In an automatic reclosing circuit breaker control system, first, second, and third control conductors extending between a circuit breaker and a control station, closing means for the circuit breaker, a closing relay adjacent the circuit breaker for actuating said circuit breaker closing means, a tripping means for the circuit breaker, means at the control station including said first control conductor for energizing the closing relay, means at the control station including said second conductor for actuating said tripping means to open the breaker, circuit means including said first control conductor responsive to the opening of the circuit breaker for energizing said closing relay to automatically reclose the breaker, a release relay at the control station, circuit means including said third control conductor responsive to the actuation of the said closing relay and the reclosure of the circuit breaker for energizing said release relay, and means whereby the actuation of said release relay opens the energizing circuit for said closing relay to prevent a second reclosure of the breaker in the event that it is tripped following the first reclosure thereof.

5. In an automatic reclosing circuit breaker control system, first, second, and third control conductors extending between a circuit breaker and a control station, closing means for the circuit breaker, a closing relay adjacent the circuit breaker for actuating said circuit breaker closing means, a tripping means for the circuit breaker, means at the control station operable over said first control conductor for energizing the closing relay, means at the control station operable over said second conductor for actuating said tripping means, circuit means including said first control conductor responsive to the opening of the circuit breaker for energizing said closing relay to effect an automatic reclosure of the breaker, a release relay at the control station, circuit means including said third control conductor responsive to the actuation of the said closing relay and the reclosure of the circuit breaker for energizing said release relay, means whereby the actuation of said release relay opens the energizing circuit for said closing relay to preclude a second automatic reclosure of the breaker in the event that the breaker is tripped following the first reclosure, and manually releasable means at the control station for holding the release relay in actuated position.

6. In an automatic reclosing circuit breaker control system, first, second, and third control conductors extending between a circuit breaker and a control station, means actuatable at the control station and including said first conductor for closing the circuit breaker, means actuatable at the control station and including said second conductor for tripping the circuit breaker,

means responsive to the opening of the circuit breaker and including said first conductor for automatically reclosing the breaker, means at the control station operable in response to the reclosure of the breaker by means including said third conductor for rendering the said means responsive to the opening of the breaker ineffective to effect another reclosure of the breaker in the event that it opens in response to the first reclosure, and means at the control station responsive to the position of the breaker and including said second conductor for indicating the breaker position.

7. In an automatic reclosing circuit breaker control system, first, second, and third control conductors extending between a control station and a circuit breaker, closing means for the circuit breaker, tripping means for the circuit breaker, means actuatable at the control station and including said first control conductor for actuating the breaker closing means, means actuatable at the control station and including said second control conductor for actuating said breaker tripping means, means responsive to the opening of the circuit breaker and including said first control conductor for actuating said breaker closing means to automatically reclose the breaker, means at the control station operable in response to the reclosure of the breaker by means including said third control conductor for rendering the means responsive to the opening of the breaker ineffective to effect another reclosure of the breaker, and means at the control station responsive to the position of the breaker and including said second control conductor for indicating the open or closed position of the breaker.

8. In an automatic reclosing circuit breaker control system, first, second, and third control conductors extending between a control station and a circuit breaker, closing means for the circuit breaker, tripping means for the circuit breaker, means actuatable from the control station and including said first control conductor for actuating the closing means to close the breaker, means actuatable from the control station and including said second control conductor for actuating said breaker tripping means to open the breaker, means responsive to the opening of the circuit breaker and including said first control conductor for actuating said breaker closing means to automatically reclose the breaker, means at the control station operable in response to the reclosure of the breaker by means including said third control conductor for rendering the means responsive to the opening of the breaker ineffective to effect a second reclosure of the breaker in the event that it reopens within a predetermined interval after the reclosure thereof, indicating means at the control station, and means responsive to the position of the breaker and including said second control conductor for causing said indicating means to indicate the position of the circuit breaker.

9. In an automatic reclosing circuit breaker control system, first, second, and third control conductors extending between a circuit breaker and a control station, closing means for the circuit breaker, a closing relay adjacent the circuit breaker for actuating said circuit breaker closing means, a tripping means for the circuit breaker, means at the control station operable over said first control conductor for actuating the closing relay to close the breaker, means at the

control station operable over said second conductor for actuating said tripping means, circuit means including said first control conductor responsive to the opening of the circuit breaker for energizing said closing relay to automatically reclose the breaker, a release relay at the control station, circuit means including said third control conductor responsive to the actuation of the said closing relay and the closing of the circuit breaker for energizing said release relay, means whereby the actuation of said release relay opens the energizing circuit for said closing relay to prevent a second automatic reclosure of the breaker, indicating means at the control station, and means including said second control conductor controlled by the position of the circuit breaker for indicating the position of the circuit breaker at the control station.

10. In an automatic reclosing circuit breaker control system, first, second, and third control conductors extending between a circuit breaker and a control station, closing means for the circuit breaker, a closing relay adjacent the circuit breaker for actuating said circuit breaker closing means, a tripping means for the circuit breaker, means at the control station operable over said first conductor for actuating the closing relay to close the breaker, means at the control station operable over said second conductor for actuating said tripping means to open the breaker, circuit means including said first conductor responsive to the opening of the circuit breaker for energizing said closing relay to automatically reclose the breaker, a release relay at the control station, said relay having manually releasable means for holding it in an energized position, circuit means including said third conductor responsive to the actuation of the said closing relay and the closing of the circuit breaker for energizing said release relay, means whereby the actuation of said release relay opens the energizing circuit for said closing relay to prevent a second automatic reclosure of the breaker, indicating means at the control station, and means including said second control conductor controlled by the position of the circuit breaker for operating said indicating means to indicate the position of the circuit breaker at the control station.

11. In an automatic reclosing circuit breaker control system, first, second, and third control conductors extending between a circuit breaker station and a control station; a source of control power common to said stations; a closing relay for the breaker; a tripping relay for the breaker; a closing circuit extending from said one terminal of the source of control power at the control station to the other terminal of the source of control power at the breaker station and comprising a first circuit control device and a second circuit control device at the control station, said first control conductor and the closing relay at the breaker station; a tripping circuit extending from one terminal of the control power source at the control station to the other terminal of the control power source at the breaker station and comprising a circuit control device at the control station, said second control conductor, said tripping

device and circuit contact element actuatable to closed position by the closure of the circuit breaker; a release relay at the control station for opening one of the circuit control devices in the closing circuit when actuated; means responsive to the closure of the circuit breaker and including said third control conductor for actuating said release relay to open the closing circuit; manually releasable means for holding said release relay in actuated position whereby the closing circuit is retained in an opened condition to preclude a second automatic reclosure, means responsive to the position of the circuit breaker for connecting said second conductor to one or the other of the terminals of the source of control power at the breaker station; a pair of indicating devices connected in circuit relation across said source of control power at the control station; and means connecting said first conductor between said indicating means.

12. In an automatic reclosing circuit breaker control system, first, second, and third control conductors extending between a control station and a circuit breaker station; a source of control power common to said stations, a tripping means for the circuit breaker; a closing relay for the circuit breaker; an energizing circuit for the closing relay including a control switch at the control station and said first control conductor; a tripping circuit extending from one terminal of the control power source at the control station to the other terminal of the control power source at the breaker station and comprising a circuit control device at the control station, said second control conductor, said tripping device and a circuit control element actuatable to closed position by the closure of the circuit breaker; a reactor at the control station having a saturating winding and a reactive winding; a series circuit extending from the one terminal of the source of control power at the control station through said saturating winding of the reactor to the said second conductor and including a first indicating device; a timing device; means responsive to the opening of the breaker and including said first conductor for energizing the closing relay to automatically reclose the breaker; relay means at the control station operated over said third control conductor responsive to the reclosure of the circuit breaker for opening the energizing circuit of the closing relay to preclude a second automatic reclosure of the breaker and for closing an alternating current circuit through said timing device and said reactive winding; means controlled by said timing device for opening the timing device circuit and operating said relay means to close the closing relay circuit after a predetermined interval of energization of the timing device; a second indicating device, a circuit connecting said second indicating device between said second conductor and the said other terminal of the source of control power at the control station; and a circuit controlled by the opening of the circuit breaker for connecting said second conductor to the said one terminal of the source of control power at the breaker station.

MAURICE E. REAGAN.
